UNITED STATES PATENT OFFICE.

ALGERNON S. HUBBELL, OF NORWICH, CONNECTICUT, ASSIGNOR TO ANSON GARDNER, OF SAME PLACE.

UMBRELLA.

SPECIFICATION forming part of Letters Patent No. 453,301, dated June 2, 1891.

Application filed December 17, 1890. Serial No. 375,036. (No model.)

To all whom it may concern:

Be it known that I, ALGERNON S. HUBBELL, a citizen of the United States, residing at Norwich, in the county of New London and State 5 of Connecticut, have invented certain new and useful Improvements in Umbrellas, which improvements are fully set forth and described in the following specification, reference being had to the accompanying sheet of 10 drawings.

This invention is in the class of umbrellas that may be folded and packed into small space, a type of said class being seen in my patent, No. 383,128, issued May 22, 1888.

15 The object of this present invention is to simplify somewhat the construction of the rib-joint in such umbrellas, and also to render the operation of unlocking the rib-joint when about to fold the umbrella less laborious and 20 less complicated than heretofore.

In my earlier patent, above referred to, the rib was jointed midway of its length and a spring-pressed sliding bolt provided in one 25 section that entered a coincident slot in the opposite section when the umbrella was opened. This bolt had a lateral projection that could be reached by a finger-nail to draw the bolt back and so unlock the rib. Such a 30 form of bolt I have found to be unnecessary and also somewhat difficult to operate, and I have therefore invented the locking-joint illustrated in the annexed sheet of drawings, Figure 1 being a view of a complete rib with 35 stretcher attached; and Fig. 2 an enlarged side view of the joint and parts of the connected rib and stretcher, the joint being shown as locked. Fig. 3 is a similar view of the same parts with the joint opened. Fig. 4 is a longitudinal sectional view of the joint; 40 and Fig. 5 a top view of that portion of the rib which forms the locking-bolt and which contains the spring that actuates said bolt.

In the drawings, *a* and *b* denote the two 45 sections which form the hinge of my locking-joint, said sections being connected by a pin-tle or pivot *c* and provided with lateral wings *d*, to which the stretcher *e* is riveted, and between which the locking-bolt passes when the umbrella is opened. The rib-section *h* is 50 cured rigidly in the hinge-section *a*, as in my earlier patent, but instead of securing the

companion rib-section *h'* in the end of hinge-section *b* and providing a separate bolt, as before, I have now extended said rib, so that its end projects through section *b*, and have left 55 it free to be moved longitudinally within said hinge-section a limited distance, thus making it possible to utilize said projecting end as a bolt that may enter between the wings *d*.

The rib as illustrated is of the form commonly known as the "paragon" rib, and is struck or rolled up from sheet metal. The end of section *h'* that is to serve as the bolt is pinched together, as at *h²*, and immediately in the rear of said pinched end (within the rib) 65 is a spiral spring *i*, whose opposite end abuts a lip *k*. The spring *i* acts with a constant tendency to force the rib *h'* to the left hand, as illustrated in the drawings. To prevent said rib from moving too great a distance, I "crimp" 70 or squeeze it together, as at *h³*, just beyond the described lip *k*, thus providing a stop that may engage said lip and limit the forward movement of the bolt.

When it is desired to close and fold an umbrella having my newly-invented lock-joint, it is only necessary to seize the ends of the ribs *h'* and pull them outward against the force of springs *i*. This withdraws ends *h²* of said ribs from between the wings *d*, and 80 the ribs may then be folded into one-half the length which they assume when the umbrella is in use. This manner of releasing the locking-bolt is much more satisfactory than that necessary in my former patent, and also dispenses with the separate bolt required in said 85 patent.

Having described my invention, I claim—

1. In a folding umbrella, the combination, with a locking-joint composed of two sections 90 hinged together, of a stretcher and a rib composed of two pieces, one of which and the stretcher are secured to one of the joint-sections and the other piece of the rib projects through and is movable longitudinally within 95 the other joint-section with its inner end adapted to engage with the end of the stretcher and lock the rib, and means for automatically moving the rib-section in one direction and limiting the scope of such movement, substantially as described.

2. In a folding umbrella, the combination,

with a locking-joint composed of two sections hinged together, one of which is provided with a lip, of a stretcher and a rib composed of two pieces, one of which and the stretcher are secured to one of the joint-sections and the other piece of the rib is closed at its inner end and contracted near the end and is movable longitudinally within the other joint-section,

and a spring within the rib between the closed end and the lip of the section to force the end of the rib under the end of the stretcher and lock the rib, substantially as described.

ALGERNON S. HUBBELL.
